UNITED STATES PATENT OFFICE.

CHARLES R. BIRDSEY, OF HINSDALE, ILLINOIS, ASSIGNOR TO UNITED STATES GYPSUM COMPANY, OF CHICAGO, ILLINOIS, A CORPORATION OF ILLINOIS.

PLASTER BOARD.

1,406,967.

Specification of Letters Patent. Patented Feb. 21, 1922.

Original application filed January 2, 1920, Serial No. 348,943. Divided and this application filed January 3, 1921. Serial No. 434,653.

To all whom it may concern:

Be it known that I, CHARLES R. BIRDSEY, a citizen of the United States, residing at Hinsdale, in the county of Du Page and 5 State of Illinois, have invented certain new and useful Improvements in Plaster Board, (Case E-1), of which the following is a description.

My invention belongs to that general class 10 of devices known as plaster board or the like, and relates particularly to an improved board which will be simple, substantial, durable, satisfactory and efficient, and which may be economically and accurately manufactured. The invention relates particularly 15 to a type of board in which the inclosed plaster, plaster Paris or equivalent plastic material is substantially inclosed on one or more edges, and in which the edges are perfectly formed to conform to a definite specification as to size or angle. Many other 20 objects and advantages of the construction herein shown and described will be obvious to those skilled in the art from the 25 closures herein given. This application is a division of my pending application Serial No. 348,943.

To this end my invention consists in the 30 novel construction, arrangement and combination of parts herein shown and described, and more particularly pointed out in the claims.

In the drawings, wherein like reference 35 characters indicate like or corresponding parts,

Figure 1 is a sectional view through a portion of a plaster board embodying the invention; and

Figure 2 is a perspective view of a portion 40 of the board.

Referring to the drawings 1 represents a body of suitable material, as for example plaster, plaster Paris or any equivalent suitable for the purpose. I prefer to use a material which may be handled in a plastic state 45 during the manufacture of the board, and thereafter be allowed to set or harden. As shown the board 1 is inclosed between covering sheets on opposite faces or sides, and 50 closed at the side edges. In the particular type of board shown, a covering sheet 2 on one face is wrapped or folded over the edges as at 3 to inclose the same, and then the portions 4 and 5 wrapped or folded over the

top face to form the covering sheet at that 55 side. The sheet is preferably of such a width that the two edges will extend substantially close together, as indicated at 6. I have also shown a strip 7 arranged in the body below the meeting edges. The covering sheet adheres to the body and is caused to adhere or be bound to the strips 7 at the edges 4 and 5 by means of the body material 8, which is allowed to flow or be pressed over the same, forming a binder. Obviously, any equivalent securing means may be employed for the purpose.

The edges 3 may be formed at the desired angles, and if desired, the sheet may be scored as at 9-9 before folding or bending so as to form sharp corners. This, however, is a matter of preference.

It will be noted that the board is substantially completely inclosed at both sides or faces and edges. The resulting product 75 is produced with a straight, smooth edge, and at a desired, perfect angle, the board being uniform in length. The completed product has may advantages, as it has increased strength and durability, and an improved appearance. The edges are protected during handling so that there is no sifting out or powdering of the board at the edges. While I have shown but two sides or edges 80 inclosed, the remaining edges may be inclosed in any suitable manner, if so desired.

Having thus described my invention, it is obvious that various immaterial modifications may be made in the same without departing from the spirit of my invention; 90 hence I do not wish to be understood as limiting myself to the exact form, construction, arrangement and combination of parts herein shown and described, or uses mentioned.

What I claim as new and desire to secure 95 by Letters Patent is:

1. A plaster board comprising a body, a cover sheet extending over one face of the body and folded over the edges onto the opposite side of the body with the edges 100 adjacent each other, and a sealing strip arranged over said body at the junctures of said edges on the interior of the cover sheet.

2. A plaster board comprising a body, a cover sheet extending over one face of the body and wrapped over the edges onto the opposite side of the body with the edges 105 adjacent each other, and a sealing strip ar-

ranged over said body at the junctures of said edges on the interior of the cover sheet, and secured to said sheet at said edge by the body material.

5 3. A plaster board comprising a body, a cover sheet extending over one face of the body and folded over the edges onto the opposite side of the body with the edges adjacent each other, and a sealing strip arranged over said body between the body and sheet at the junctures of said edges.

10 4. A plaster board comprising a plaster body, a cover sheet extending over and adhering to one face of the body and folded

over the edges onto the opposite side of the 15 body and adhering thereto, with the extreme edges adjacent each other, and a sealing strip arranged over said body between the body and sheet at the junctures of said edges, said edges and strip secured together. 20

In testimony whereof, I have hereunto signed my name in the presence of two subscribing witnesses.

CHARLES R. BIRDSEY.
